UNITED STATES PATENT OFFICE.

ERASTUS S. BENNETT, OF NEW YORK, N. Y.

SCREW-PUMP.

968,829.

Specification of Letters Patent. Patented Aug. 30, 1910.

Application filed May 15, 1909. Serial No. 496,259.

To all whom it may concern:

Be it known that I, ERASTUS S. BENNETT, citizen of the United States, residing at New York city, New York, have invented 5 certain new and useful Improvements in Screw-Pumps, of which the following is a specification.

My invention relates to the general form of screw pump disclosed in application for 10 Letters Patent of the United States filed by me August 28, 1908, #450707. In said application I disclose means for eliminating the effect of skin friction of the blades upon the body of water to be forced, said means 15 consisting of a diaphragm or diaphragms interposed in the screw blades or between the sections thereof, the said diaphragms having openings for the passage of the water forced by the blades.

20 My present improvement relates to means for holding these diaphragms in place, and also to the construction of the openings through these diaphragms whereby an effectual stop for the back drag or back pressure 25 of the water, which results from the skin friction existing between the blade and the body of water, or from other causes, is provided for and rendered practically negligible.

30 In the accompanying drawings Figure 1 is a sectional view through a screw pump embodying my invention; Fig. 2 is a view of one of the diaphragms within the cylinder; Fig. 3 is a sectional view of Fig. 2; 35 Figs. 4 and 5 are views similar to Figs. 2 and 3 of the diaphragm at the head of the cylinder; Fig. 6 is a detail view of one of the heads without a diaphragm but with a division web; Fig. 7 is a sectional view in 40 the nature of a diagram showing the ends of the screw blades in their relation to the diaphragms; Fig. 8 is a detail sectional view.

In these drawings, 1 indicates the inlet casing, 2 the outlet casing, 3 the pump cylinder arranged between these casings, 4 the screw piston, and 5 the diaphragm, of which there may be one or more, according to the extent or number of the screw blades. For 45 holding these diaphragms in place, I provide a series of sleeves or collars 6 which are fitted to the interior of the cylinder and are interposed between the diaphragms and between the heads of the cylinder and the said diaphragms, these collars being long

enough to separate the diaphragms and the 55 heads for the proper amount of clearance for the working of the screw blades.

As in the application above mentioned, the effect of the use of the diaphragms is that the body of water having been forced 60 longitudinally of the cylinder by one of the screw blades, will be separated from this screw blade which has propelled it, so that it will be relieved of the back motion resulting from skin friction and may be acted on 65 anew by a second blade forming, in effect, a continuation of the first blade section. The blade sections rotate in close proximity to the faces of the diaphragms so that, in the revolution of the screw, the blades will 70 cut off the water at the inlet openings and press this cut off portion forward through the opening in the diaphragm, and immediately upon its passage through the dia- 75 phragm the effect of skin friction will be eliminated and the body of water will be subjected to the action of the next section of the screw blade, and so on throughout the cylinder. The collars 6 fit tightly in the cylinder and serve to properly space the 80 diaphragms, and to hold them against circumferential displacement. It will be observed that the openings through the dia- 85 phragm are of conical form with the smaller end toward the discharge end of the cylinder. By this construction I secure an automatic stop, or what may be called a water stop valve, for it will be understood that the column of water pressed through the openings will be equal in diameter to the 90 smaller end of the opening, and the water having passed through, will find a back stop or arresting surface on the plain face of the diaphragm surrounding the contracted end of the opening, and any back 95 pressure resulting from the effect of the inclined blade on the water or from other causes will be taken up by this straight bearing and will be prevented from passing back through the diaphragm to the inlet 100 side thereof.

In the operation of the device, any back pressure existing in the water, by its action upon the plain face of the diaphragm on its discharge side, will set up eddy currents 105 which will act across the smaller outlet ends of the nozzle-like openings and form a water lock at these points to prevent the backward

passage of water or pressure from the discharge to the inlet side of the diaphragms and of the pump. The construction provides, in effect, an automatic check valve where we are dealing with water under pressure, or, more properly speaking, a water lock to prevent back flow.

It is evident that the water will be always under the heaviest pressure at the small end of the nozzle-shaped opening, and it is this pressure which must be overcome by the back pressure whether due to skin friction or to the head or column of water being forced or lifted before there can be any back flow of water through the diaphragm, but, as set forth above, back pressure will form a water lock on the plain discharge side of the diaphragm, and this water lock will increase in effect proportionately to the tendency to back pressure which the water may have.

The tapering nozzle openings, at their larger ends, extend practically from the shaft or rather the hub of the screw blade to the inner periphery of the spacing rings so that they present no flat obstructing surfaces on their inlet sides, but they do present such surfaces on their outlet sides to prevent back flow.

As will be seen from Figs. 2 and 3, the diaphragms have inner and outer rings connected by spokes, and both the rings, as well as the spokes, taper toward their inlet sides. The same is true of the diaphragms at the heads of the cylinder. By this construction not only is no obstruction offered to the flow of the water, but the aggregate area of the openings through either diaphragm on the inlet side is equal to the area of the cross sectional inlet and outlet pipes minus the thickness of the spokes. By this construction a stream will be delivered approximately equal in cross sectional area to the cross sectional area of the inlet or discharge pipe or of the cylinder.

The ring spacing of the diaphragms facilitates quick and accurate adjustment of the diaphragms in manufacturing. The rings take the wear from the cylinder proper, and are readily replaced. They also obviate the necessity for accurately boring the cylinder.

While the spokes or arms of the diaphragm are shown as radial, I do not confine myself in this regard.

Instead of having an end head provided with a vertical web dividing the inlet and the outlet, as shown in Fig. 6, I prefer to provide a diaphragm at each of these heads. In the construction shown in Fig. 6, the vertical web furnishes only two opposing surfaces to coöperate with the screw blade. I have improved this construction by cutting the web or partition away at the face side of each head so as to permit the insertion of a diaphragm indicated at 5^x, Figs. 1, 4 and

5. These diaphragms project slightly into the cylinder, and, if desired, instead of being inserted in the heads, they may be cast in. The eight or more webs furnished by these diaphragms coöperate with the screw blades by holding the water to secure the shearing effect on the water at the inlet end of the apparatus, and the forcing effect or what may be termed a "plastering" effect at the discharge end where the screw blade forces the water forward through the head. In this construction, a part of the vertical web used in my previous construction is dispensed with, and the diaphragm takes its place. The openings through this head diaphragm are not necessarily of a tapered form, though they should be tapered when the pump is designed to work against pressure. In case the head diaphragms are not cast with the heads, they will, of course, be set so that the vertical partitions of the diaphragms will register with the vertical edge of the dividing web in the head.

The diaphragms within the cylinder, as above stated, are held in position by spacing rings. These diaphragms are preferably shouldered, leaving a projecting annular rim at 7 against which the spacing rings abut. These spacing rings may be intact throughout the extent of each, or they may be split rings or formed in sections. Their edges fit between the shouldered portions of the diaphragms and the interior periphery of the cylinder, or their edges may abut against the sides of shoulderless diaphragms.

The form or taper of the spokes of the diaphragm will depend upon the work the pump is intended to do, thus for volume pumping they are only slightly tapered, whereas for pumping against strong back pressure or for lifting against a considerable head, they are tapered more sharply. In my improved arrangement with the tapered openings, the area at the discharge end of the tapered openings is less than the area at the inlet, and this enables me to pump against a heavier back pressure or a greater head than would otherwise be the case. Each spoke in the diaphragms presents a knife edge to the incoming fluid.

In the form of the invention having the web at the inlet and the web at the outlet, the purpose of the web is to hold the fluid at the inlet against its tendency to swirl away from the shearing end of the revolving screw blade, and at the outlet the purpose is to scrape or take the water from the blade as it sweeps past the inner edge of the said web. The diaphragm presents a series of these webs or fixed shear members to coöperate with the revolving screw, each spoke tending to hold the water so that it cannot swirl away from the oncoming blade.

I claim as my invention:

1. In combination in a screw pump, a

5 cylinder, a screw piston and a diaphragm having an inner ring tapering from its outlet side to its inlet side and toward the axis of the piston, and an outer ring tapering from its outlet side to its inlet side and toward the cylinder wall, both of said rings on the outlet side of the diaphragm having an exposed flat surface or projection to form a back stop for the water after passing through the diaphragm, the blade of the screw operating close against said stop, substantially as described.

10 2. In combination in a screw pump, a cylinder, a screw piston and a diaphragm having openings therethrough, the inner walls of which taper from the outlet side to the inlet side toward the axis of the piston and the outer walls of which incline from the outlet side to the inlet side toward the cylinder wall, said diaphragm on its outlet side having flat surfaces or projections to form a back stop for the water after passing through the diaphragm, the blade of the screw operating close against said stop.

15 3. In combination in a screw pump, a cylinder, a screw piston therein, a diaphragm consisting of an inner ring at the hub of the piston, an outer ring at the cylinder and spokes connecting said rings, both 20 the inner and outer rings and the spokes tapering to the inlet side of the diaphragm, and presenting tapered openings reaching from the hub of the screw piston to the cylinder, and tapering from the inlet to the 25 outlet sides of the diaphragm, and with flat surfaces exposed on the outlet side about the openings substantially as described.

4. In combination a cylinder, a screw piston therein, heads at the ends of the cylinder, diaphragms within the cylinder and diaphragms at the heads having a plurality of spokes to coöperate with the screw, said 30 last mentioned diaphragms being held in seats in the heads and having openings be-

35 tween the spokes tapered on all sides, substantially as described.

5. In combination in a pump, a cylinder, a screw piston therein, an inlet and a discharge section, and a division member or spoke at the said inlet and outlet coöperating with the screw piston, and each beveled on its inlet side, the said screw piston operating close against the flat side of the said inlet division member, substantially as 45 described.

6. In combination in a screw pump, a cylinder, a screw piston operating therein, a head connected with the cylinder, a division wall or web in said head providing a plurality of passages leading to the cylinder, a diaphragm interposed between the said head and the cylinder, said diaphragm having a plurality of openings extending therethrough, substantially as described.

7. In combination in a screw pump, a cylinder, a screw piston therein, a diaphragm having a plurality of openings with outwardly extending spokes forming the side walls thereof, said spokes being beveled on the inlet side of the diaphragm, the 60 said screw piston operating close against the flat outlet side of the spoke, substantially as described.

8. In combination a cylinder, a screw therein, heads at the end of the cylinder, 65 diaphragms within the cylinder and diaphragms at the heads having a plurality of spokes to coöperate with the screw, said last mentioned diaphragms being held in seats in the heads and having openings between 70 the spokes tapering on all sides substantially as described.

In testimony whereof, I affix my signature in presence of two witnesses.
